CARD PUNCH OR THE LIKE

George H. Kress, Newark, N.J., assignor to Business Research and Engineering Corporation, Ardmore, Pa., a corporation of Delaware

Filed Sept. 27, 1963, Ser. No. 77,046

Term of patent 14 years

(Cl. D64—11)

FIGURE 1 is a front perspective view of a card punch or the like, showing my new design; and

I claim:

The ornamental design for a card punch or the like, substantially as shown.
